SELECTIVITY CONTROL

James E. Beggs, Schenectady, N. Y., assignor to
 General Electric Company, a corporation of
 New York

Application December 2, 1936, Serial No. 113,866

3 Claims. (Cl. 250—20)

My invention relates to radio receiving apparatus and particularly to such apparatus which is provided with selectivity control. Many forms of such apparatus as heretofore proposed have been subject to the objection that each time the apparatus is tuned to a different station it has been necessary in order to obtain proper tuning for the operator to actuate some device to change the apparatus from a condition of high fidelity to one of high selectivity, then after tuning is completed to change it back to a condition of the desired higher fidelity.

It is the object of my invention to provide improved apparatus of this character by which this objection is overcome.

In accordance with my invention I have provided radio receiving apparatus having means for varying the selectivity thereof and having a tuning device adapted to be actuated by the hand 20 of the operator, the arrangement being such that the conductivity of the hand of the operator on the device functions to cause the desired increase in the selectivity; likewise the removal of the hand of the operator from the device causes a 25 restoration of the original selectivity.

My invention will be understood from the following description taken in connection with the accompanying drawing, and its scope will be pointed out in the appended claims.

30 In the single figure of the drawing, which is a circuit diagram illustrating my invention which is shown as forming a part of a superheterodyne radio receiving system, 1 is the antenna or pick-up device, 2 is the radio frequency amplifier stage, 3 is the detector and oscillator stage, 4 is the stage of intermediate frequency amplification, 5 is the second detector and automatic volume control stage, 6 is the audio amplifier, and 7 is the loudspeaker. The detector and oscillator stage 3 is shown coupled to the intermediate frequency amplifier stage 4 by the coupling transformer 10 having the primary winding 11 and the secondary winding 12 tuned to the intermediate frequency by the adjustable capacitors 13 and 14 respectively. The primary and secondary windings 11 and 12 are wound in the same direction on the same axes, the windings being normally somewhat loosely coupled whereby a relatively high degree of selectivity results in which condition 50 the apparatus is well adapted to be accurately tuned to a desired carrier.

In order that the apparatus may exhibit greater fidelity than that obtained with its natural high selectivity, I have shown means, now to be described, for increasing the effective coupling

between the primary and secondary windings of the transformer. This means comprises the phase shifting network 16 including the capacitor 17 and the resistor 18 connected in series between the upper end of the secondary winding 12 and ground through the bypass capacitor 19. The impedance of the capacitor 17 is large with respect to that of the resistor 18 at the intermediate frequency employed so that the current in the resistor 18 and hence the voltage across the resistor is nearly 90° ahead of the voltage across the secondary winding 12. This phase displaced voltage is amplified by the electron discharge amplifier 20 and applied to the primary winding 11 to produce an effective increase in the coupling 15 of the transformer.

For the above-mentioned amplification of the phase displaced voltage in the resistor 18 a point of the network 16 intermediate the capacitor and the resistor connects by the conductor 21 with the grid 22 of the amplifier 20 and the anode 23 connects by the conductor 24 with the upper end of primary winding 11, the lower end of which connects with ground through the bypass capacitor 25. The cathode 26 of the amplifier 20 connects with a source of voltage, not shown, which, for example, may be plus 10 volts.

The apparatus is provided with a special form of hand operated tuning device, or knob, which for example may be like that shown at 30. The 30 knob 30 which may be of insulating material preferably has the two metallic rings 31 and 32 embedded therein but insulated from each other which rings are adapted to be connected together by the fingers of the operator when the 35 knob is turned for changing the tuning of the apparatus. Ring 32 connects with ground and ring 31 connects through the resistor 33 with the lower end of the resistor 18. A positive voltage is supplied to the ring 31 and through the resistor 33 to the lower end of the resistor 18 by means of the potentiometer 34 one end of which is represented as being at a potential of plus 3 volts and the other end at a potential of plus 8 volts, the movable arm of the potentiometer 45 including the resistor 35.

In the normal use of the apparatus at which time the hand of the operator is not in contact with the tuning knob 30, a positive voltage is supplied to the grid 22 of the amplifier 20 50 through the resistor 18 of the phase shifting network such that the amplified phase displaced voltage from that network is supplied to the primary 11 to produce an increase in the coupling of the transformer 10 to give the desired degree 55

of fidelity. When, however, the operator grasps the tuning knob 30 to change the tuning of the apparatus, for example to receive signals from a different station, the presence of his fingers on the tuning knob in a position connecting the rings 31 and 32 thereof reduces the voltage applied by the potentiometer to the grid 22 of the amplifier 20 to a value sufficiently negative with respect to the cathode 26 so as to cut off the amplifier or reduce its output to a negligible value. Thus while the knob 30 is being turned by the operator to tune the apparatus, there is little or no phase displaced voltage supplied to the primary 11 and accordingly the coupling of the transformer automatically returns to its original loose condition at which the selectivity of the apparatus is relatively high. Upon removal of the fingers from the tuning knob the amplifier 20 again becomes operative and the resulting effective increase in coupling of the transformer 10 restores the fidelity of the apparatus although at some expense of selectivity.

In the drawing I have shown the amplifier 4 connected with the second detector stage 5 through the coupling transformer 10' which may be similar to that shown at 10. The primary of this transformer also may be supplied with a phase displaced voltage from the phase shifting network 16' similar to that shown at 16 and amplified by the amplifier 20' which is similar to that shown at 20. Since the transformer 10', the phase shifting network 16', and amplifier 20' are like the corresponding parts already described, a detail description thereof seems to be unnecessary and will not be made.

I have chosen the particular embodiment de-

scribed above as illustrative of my invention and it will be apparent that various modifications may be made without departing from the spirit and scope of my invention which modifications I aim to cover by the appended claims.

What I claim as new and desire to secure by Letters Patent of the United States is:

1. Radio receiving apparatus provided with a hand operated tuning knob, said knob having normally insulated conducting portions arranged to be touched simultaneously by the hand of the operator when changing the tuning of the apparatus and means responsive to the simultaneous touching of said portions by the hand of the operator for increasing the selectivity of the apparatus.

2. Radio receiving apparatus provided with a hand operated tuning knob, said knob having spaced conducting portions insulated from each other and arranged to be bridged by the hand of an operator, means for causing said apparatus to have a predetermined degree of selectivity and means controlled by the bridging of said conducting portions by the hand of the operator for increasing the selectivity of said apparatus.

3. Radio receiving apparatus including a coupling transformer and a hand operated tuning knob constructed of insulating material and having spaced conducting portions arranged to be bridged by the hand of an operator, means operative to increase the effective coupling of said transformer and means controlled by the bridging of said conducting portions by the hand of the operator for rendering said means inoperative.

JAMES E. BEGGS.
